INVENTOR

Antonio Troiano

BY
Geo. W. M. Murch
ATTORNEY

UNITED STATES PATENT OFFICE.

ANTONIO TROIANO, OF YONKERS, NEW YORK.

SANITARY APPLIANCE.

1,243,462.

Specification of Letters Patent. Patented Oct. 16, 1917.

Application filed June 22, 1917. Serial No. 176,362.

To all whom it may concern:

Be it known that I, ANTONIO TROIANO, a citizen of the United States, and a resident of Yonkers, county of Westchester, 5 and State of New York, have invented certain new and useful Improvements in Sanitary Appliances, of which the following is a specification.

My improvements, although applicable in 10 a general way, relate more particularly to sanitation in barber shops, hospitals, and like situations where aprons, napkins, and similar articles, adapted to be fitted closely around the neck of the wearer, are used. In Letters Patent No. 1,188,512, issued to me June 27, 1916, I set forth discardable means for interposition between the neck of the wearer and the apron or sheet used for shielding the clothing etc.,—the discardable means 15 20 alone contacting with the skin of the wearer, such discardable means preventing the contamination of the apron or sheet so that the latter may be safely used again without danger of the possible transmission of disease or infection.

The object of my present invention is to 25 provide means whereby the discardable protective collar or neck band may be of the simplest and cheapest material and form or 30 structure, and to obviate the need of special fastening devices for either collar band or shielding cloth or apron; and the invention consists essentially in providing said external shielding cloth or apron with an elastic 35 resilient clasp adapted to encircle the discardable protective collar or neck band, said clasp being readily sprung into or out of engagement with discardable strip after the latter has been positioned upon and around 40 the neck of the wearer, as hereinafter more fully set forth.

In the accompanying drawings,

Figure 1, is a rear view of a dummy illustrating the practical use of my invention in 45 conjunction with a barber's apron or similar shielding cloth;

Fig. 2, is a view of a flat elastic resilient spring adapted for use as a clasp;

Fig. 3, is a detail view of a portion of a 50 discardable protective neck band suitable for use for the purpose designated;

Fig. 4, is a cross section of the dummy

taken upon plane of line 4—4, Fig. 1, the spring casing being broken away to show the spring;

Fig. 5, is a cross section illustrating the relative positions of the parts in use;

Fig. 6, is a detail view of a portion of the apron or shield cloth formed with a casing for the spring, which latter is shown as 60 protruding therefrom.

The discardable collar or neck band *b*, 65 may consist of a flexible strip of any suitable material, preferably a strip of cotton sheet wadding (so called commercially) on account of its cheapness, softness, and adaptability for the purpose herein designated. This band *b*, is of a length sufficient to encircle the neck of an ordinary individual and of a width sufficient to afford a 70 bearing for the apron or shield cloth *c*, in such manner that the latter need not contact directly with the neck of the wearer.

The neck portion or edge of the apron or shield cloth *c*, is held against the discardable neck band *b*, by an elastic resilient spring *s*, preferably although not necessarily of flat form as shown in Fig. 2, of the drawings, and made of spring metal, celluloid or any other suitable material. 75 This spring acts as a clasp to encircle the neck, and may be readily expanded and deflected to effect placement or displacement as related thereto. It is also preferably attached to the shield cloth *c*, by being inserted in a casing *c'*, formed thereon for its reception as shown particularly in Figs. 5, and 6,—the casing *c'*, being open at either end so that the spring *s*, may be removed 80 when it is desired to wash the shield cloth *c*.

It will be seen that I dispense entirely with pins, buttons, or other extraneous fastening devices, while providing effectually for maintaining the several parts in position with relation to each other in use; that 95 the operations of application or removal are simple and easy; and that the cost of the discardable neck band is reduced to the minimum. Furthermore while the incorporation of the spring clasp in a casing in the 100 shield cloth is not an indispensable feature of my invention its use in this manner renders the combination unitary in character for all practical purposes without imped-

ing the ready removal of the spring clasp when it is desired to cleanse the shield cloth.

What I claim as my invention and desire 5 to secure by Letters Patent is:

A shield cloth, a discardable neckband separate and disconnected therefrom, and an elastic resilient spring clasp discon-

nected from said cloth and band and fully endwise-movable and adapted to press the 10 neckband against the neck of the wearer and to hold the shield cloth in position.

ANTONIO TROIANO.
